UNITED STATES PATENT OFFICE.

FRANK BECKER, OF MCKEESPORT, PENNSYLVANIA.

FAUCET.

1,121,456.

Specification of Letters Patent. Patented Dec. 15, 1914.

Application filed July 22, 1913. Serial No. 780,430.

To all whom it may concern:

Be it known that I, FRANK BECKER, a citizen of the United States, and a resident of McKeesport, in the county of Allegheny and State of Pennsylvania, have invented a new and Improved Faucet, of which the following is a full, clear, and exact description.

Among the principal objects which the present invention has in view are: To provide a driving faucet having means for preventing the flow of the liquid while installing the faucet in service relation; and to simplify and economize the faucet structure.

One embodiment of the present invention is shown in the accompanying drawings, in which—

Figure 1 is a perspective view of a liquid-containing keg, a supporting buck therefor, and a faucet and cooling coil therefor, constructed and arranged in accordance with the present invention; Fig. 2 is a side elevation of the same, the buck and keg being partly cut away to show the faucet, coil, and manner of installing the same in service relation; Fig. 3 is a longitudinal, vertical section of a faucet constructed in accordance with the present invention, the section being taken on the longitudinal axis of said faucet; Fig. 4 is a plan view of the closure cap, showing in conjunction therewith the terminal ends of the cooling mat; Fig. 5 is a longitudinal, vertical section of a modified form of the faucet; Fig. 6 is a detail view showing in vertical section and in partly separated relation the driving plug, drawing tube, and faucet head, the latter being shown in the position assumed when being introduced through the driving plug; Fig. 7 is a vertical cross section taken on the line 8—8 in Fig. 7; Fig. 8 is a detail view in section, showing a fragment of the inner end of the modified form shown in Fig. 5, the chamber-closing valve being shown as seated.

The faucets and cooling coils connected therewith constructed and arranged in accordance with the present invention are designed principally for employment as means for decanting or drawing off beer from the original kegs A. The kegs, as shown in Figs. 1 and 2, are supported on bucks of suitable construction, having sides, back, a bottom 15, a front edging board 16, and a cradle brace 17, said brace being curved to conform with the general curve of the kegs of the character mentioned. The sides and

back of said buck, together with the bottom 15 and edging board 16, form a chamber 18, wherein ice, in cakes, pieces or chips, may be packed to rest upon a coil mat 19.

The mat 19 is constructed from suitable tubing, tinned or otherwise prepared to prevent crushing. The coil is preferably constructed from a continuous tube, the terminals whereof are both connected to a faucet 65 constructed as hereinafter described, wherein liquid flows preliminarily and finally through disconnected sections thereof.

The chamber 18 is provided with an overflow tube 20, the intake end 21 whereof is disposed slightly above the upper surface of the mat 19 and below the upper edge of the board 16. The delivery end 22 of said tube is connected with the waste-pipe, or other depository, as desired.

It will be noted that when the chamber 18 is packed or supplied with ice, the beer or liquid contained in the keg A is cooled thereby. It will also be noted that the liquid drawn from the keg will be subject to the influence of the cooling medium for the relatively short period necessary for the passage of the beer or liquid through said mat. In this manner, the beverage is sufficiently cooled while being drawn, and is saved from the deleterious effect of being 85 iced, or held for too long a period at a low temperature.

The preferred form of faucet used in conjunction with the present invention is that shown in Figs. 1 to 4 inclusive. The faucet therein shown consists primarily of a body portion 23, comprised in a unit casing longitudinally and centrally bored to form a continuous passageway having two sections of different diameters. The portion having the smallest diameter is contained in the tapered plug section 24. The portion having the larger diameter is wholly contained within the body portion, and within the driving head section 25.

Within the body portion 23 are disposed valve rings 26 and 27. The valve rings 26 and 27 are separated, when installed in the bore provided for them, by a packing ring 105 28 (see Fig. 3 of the drawings). The rings 26 and 27 are each pierced to form an orifice to register with bores 29 and 30 formed in the body portion 23. The bores 29 and 30 are parallel and disposed substantially 110 perpendicular to the main bore of the body portion 23. Where the bores open from the

body portion 23, said body portion is flattened to form a seat for a packing pad or disk 31. The disk 31 is normally seated in a cupped recess formed in one side of a cap 32. The cap 32 is preferably cylindrical, and is provided with an annular flange 33, which forms the pocket for the packing pad 31, above mentioned.

The body portion 23 is suitably constructed to form a rabbet seat for the flange 33. When thus constructed, the packing pad 31 is held firmly between the cap 32 and said body portion 23.

To force the cap 32 firmly in service position, a screw 34 is provided, the threads whereof engage a suitably tapped hole in the body portion 23 (see Figs. 3 and 5 of the drawings). The cap 32 is provided with side opening bores 35 and 36, each of which has a perpendicular section for register with the bores 29 and 30 formed in the body portion 23. In this position, the cap 32 is connected with the terminal ends 37 and 38 of the coil 19, the end 37 being connected with the bore 35, and the end 38 connected with the bore 36. The bores 29 and 30 register with the openings in the rings 26 and 27. In service, the openings in the rings 26 and 27 register with the inner ends 30 of tubular channels 39 and 40, formed in the inner and outer half sections of the spigot. In this position, said rings are retained by a feather 51 (see Fig. 8 of the drawings). The spigot referred to embodies an elongated tube 41, having at the inner end, perforations 42 surrounding a rounded end 43. The tube 41 may be permanently secured to the faucet head 44 in any suitable manner. The head 44 has a curved channel formed therein, in which is mounted a valve cylinder 45, which has a handle 46 connected therewith, by which said valve cylinder is rocked on its seat.

To hold the head 44 in fixed position, the section 25 is provided with a socket, into which the reduced end 47 of a bracket 48 extends when the various elements of the faucet are tightened, and where it is held by a set screw 49.

Having a faucet and coil constructed and arranged as above described, and as shown in the drawings, the operation is as follows:—The body portion 23 is separated from the tube 41 and head 44. A cork or plug 52 is placed in the inner end of the bore of the plug section 24. The plug section 24 is placed in position upon the sealing plug of the keg, and when driven by means of a mallet, the blow being delivered on the head section 25, said sealing cork is driven into the interior of the keg, the plug section 24 taking its place and closing the opening in said keg. The body portion or plug section being fixed firmly in position, the tube 41 of the faucet is passed through an open-

ing in a nut 50 and through the opening in the rings 26 and 27, until the end 43 rests against said cork or plug. Before driving the tube 41 in to dislodge the cork previously placed in the bore of the plug section 24, the said tube is upturned to close the inner ends of the channels 39 and 40. In this position, the tube 41 is driven home, dislodging the cork into the keg A. The liquid which now enters the channel 39 by way of the perforations 42, is held therein, having no avenue of escape. It will now be seen that when the faucet handle 46 is disposed to open the channel 40, the pressure in the keg A forces the liquid contained therein through the perforations 42, channel 39, bore 35, coil mat 19, bore 36, bore 30, and channel 40, for delivery. It will also be seen that the flow of liquid from the keg A is controlled by the handle 46, and that the liquid, when delivered to the receptacle for purveying the same, is cooled only when passing through the mat 19 and preliminary to being consumed. Further, it will be noted that the liquid within the keg not being subjected constantly to the refrigeration of the ice or refrigerant held in the chamber 18, the deleterious results above referred to are avoided.

In Fig. 5 is shown a modified form of the invention, the modification consisting in providing a valve 53 and a screw plug 54, in the end whereof a seat is formed for the valve 53, and the opening whereof registers with the openings of the rings 26 and 27. The valve 53 is provided as a substitute for the cork or plug with which the bore in the plug section 24 is closed when said plug section 24 is driven into the keg. In the modified form shown in Fig. 5, the tube 41 is shortened, the rounded end 43 thereof extending, in this form, to slightly beyond the screw plug 54, to introduce the perforations 42 within a chamber 55 which has direct communication with the interior of the keg through openings 56 formed in an extension 57 of the faucet. The valve 53 is normally seated by operation of a spiral spring 58. To anchor said spring, a spider 59 is mounted in the chamber 55, said spider having a central passage to guide the stem of the valve 53, and lateral openings to permit the flow of liquid through the chamber 55. The form of faucet shown in Fig. 5 is one having a connecting neck 60 for insertion through an anchor plate, to engage which, bayonet cam sections 61 are provided. The anchoring plate referred to is purposely omitted from the drawings, to avoid complication. To rotate the body portion 23 to lock the faucet in position, there is provided a hand-operated wheel 62 of suitable form and construction. When employing this form of faucet, the single difference in operation thereof as distin-

guished from that above described consists in that the rounded end 43 of the tube 41 impinges upon the valve 53 to remove the same from the seat provided therefor on the 5 screw plug 54, thus liberating the liquid which enters the chamber 55, said valve 53 having slots 63 peripherally formed therein. When, for any reason, the tube 41 is withdrawn from the body portion 23, the spring 10 58 operates to seat the valve 53 to stop the flow of liquid from the chamber 55. It will be noted that the slots 63 are not as wide as the seat formed for the valve 53. They are therefore closed by the metal forming said 15 seat.

Claims:

1. A faucet, comprising a driving plug having a longitudinal bore and spaced transverse bores connecting therewith and adapted to receive the terminals of a pipe coil; and a delivery tube fitting said longitudinal bore and rotatable therein, said tube having separated channels providing openings adapted to register with said transverse 25 bores.

2. A faucet, comprising a driving plug having a longitudinal bore and spaced transverse bores connecting therewith and adapted to receive the terminals of a pipe coil; a delivery tube fitting said longitudinal bore and rotatable therein, said tube having separated channels, providing openings adapted to register with said transverse bores; and means for locking said tube in service position. 30 35

3. A faucet, comprising a driving plug having a longitudinal bore and spaced transverse bores connecting therewith and adapted to receive the terminals of a pipe coil; a delivery tube fitting said longitudinal bore 40 and rotatable therein, said tube having separated channels, providing openings adapted to register with said transverse bores; a faucet head fixedly mounted on said tube; and means registering on said head corresponding with the driving plug. 45

4. In a liquid-dispensing faucet; a driving plug, comprising a longitudinal bore having sections of different diameters; a plurality of packing rings mounted in the 50 larger of said sections, said rings being each provided with openings to register with channels opening from said bore; a delivery tube having separated delivery channel sections the adjacent ends whereof register 55 with the openings in said rings; means providing a sliding engagement between said driving plug and said rings to hold the same in service relation; and means for locking said tube in service relation, embodying 60 a bracket on said tube, a socket in said plug, and a set screw operatively mounted in said plug.

In testimony whereof I have signed my name to this specification in the presence of 65 two subscribing witnesses.

FRANK BECKER.
